Patented May 16, 1905.

UNITED STATES PATENT OFFICE.

FREDERICK D. OWEN, OF NEW YORK, N. Y.

DESIGN FOR A DOOR-KNOB OR SIMILAR ARTICLE.

SPECIFICATION forming part of Design No. 37,484, dated May 16, 1905.

Application filed April 10, 1905. Serial No. 254,898. Term of patent 7 years.

To all whom it may concern:

Be it known that I, FREDERICK D. OWEN, a citizen of the United States, residing at New York, in the State of New York, have invented 5 a new, original, and ornamental Design for a Door-Knob or Similar Article, reference being had to the accompanying drawings.

Figure 1 is a side view of a door-knob, showing my design; and Fig. 2 is a face view
o of the same.

I claim—
The ornamental design for a door-knob or similar article, as shown.

FREDERICK D. OWEN.
